[57] CLAIM

The ornamental design for an umbrella handle, substantially as shown and described.

DESCRIPTION

FIG. 1 is a front elevation of an umbrella handle showing my new design;

FIG. 2 is a left side elevation thereof;

FIG. 3 is a rear elevation thereof;

FIG. 4 is a right side elevation thereof;

FIG. 5 is a top plan view thereof;

FIG. 6 is a bottom plan view thereof;

FIG. 7 is a front elevation of a second embodiment of that shown in FIG. 1; and

FIG. 8 is a left side elevation of that shown in FIG. 7. The undisclosed rear elevation, right side elevation, top and bottom plan views of the second embodiment are the same as that shown in the first embodiment.
